MASON'S LINE HOLDER

Roy Anders, Center Township,
Marshall County, Ind.

Application November 13, 1946, Serial No. 709,513

1 Claim. (Cl. 33—86)

1
This invention relates to improvements in masons' line holders, and particularly to a line holder of the type which is adapted to be held in place by the tension of a line drawn between the same and a similar holder at the opposite end of the line, said line holders engaging opposite ends of a wall structure.

The primary object of the invention is to provide a device of this character which is simple, sturdy and compact, which is easy to use, and which effectively holds a mason's line without interference by the line with proper seating of the holder.

A further object is to provide a device of this character which permits the line to be positioned flush with the plane of the wall structure to form a guide for the laying of masonry, which is close spaced to the masonry and at the same time permits the line to apply a tension thereon at such a position as to draw upon the holder in a manner which insures effective clamping of the holder to the building structure by the line.

A further object is to provide a device of this character which is small in size to facilitate convenient storage thereof, but which, nevertheless, accommodates the laying of masonry with the mortar joints between the masonry elements spaced in a wide range of dimensions.

A further object is to provide a device of this character which is of substantially L-shape and whose legs have inner surfaces disposed at right angles, one of said legs having a longitudinal line-receiving groove in its inner face, and the other having a central slot extending substantially the full length thereof with which said groove communicates, said first named leg having a line-anchoring member at its outer surface and having integral laterally projecting portions at its free end.

Other objects will be apparent from the following specification.

In the drawing:

Fig. 1 is a view illustrating the manner in which the device is used.

Fig. 2 is a longitudinal sectional view of the device taken on line 2—2 of Fig. 4.

Fig. 3 is an end view of the device.

Fig. 4 is an opposite end view of the device.

Fig. 5 is a perspective view of the device.

Referring to the drawing which illustrates the preferred embodiment of the invention, the numeral 10 designates a masonry wall which is formed from masonry elements 12, such as bricks, which are laid up in horizontal courses and

which are bonded together by mortar to form mortar joints 14. The wall construction may entail the use of any conventional pattern of masonry. Likewise, while the wall herein illustrated shows the masonry elements 12 as being laid in horizontal courses, it will be apparent that the item may also be used in laying up walls of stone or other masonry elements of irregular size whose horizontal joint lines may be somewhat broken and irregular for desired pattern effects, but in the laying of which a horizontal guide is desirable for proper performance of the work. The usual mason's line 16, in the nature of a strong cord of the type well understood in the art, constitutes this horizontal guide. In common practice this line is strung between nails driven into the fresh mortar at opposite ends of the building wall, which practice consumes time to insure proper locating of the nails and also time to repoint the mortar surfaces after the nails have been withdrawn therefrom. In this instance the line is anchored and held in properly tensioned relation by my novel line-holder 18.

25 The line-holder 18 is preferably formed of a light weight metal, such as aluminum or magnesium, although it may be formed of a plastic material such as a synthetic resin material, or of iron or steel. The line holder is generally of L-shape, as best seen in Figs. 2 and 5, and has a leg portion 20 and a second leg portion 22. The leg 20 is preferably of a length slightly less than one-half the width of a conventional building brick, such as a face brick, and the leg 22 is somewhat shorter than the leg 20. It will be understood, however, that these dimensions are illustrative and may vary within a wide range. The inner surface 24 of the leg 20 is preferably flat and lies in a plane perpendicular to the flat inner surface 26 of the leg 22. A groove 28 extends longitudinally and preferably centrally of the face 24 of the leg 20 for its full length. A longitudinal slot 30 is formed centrally in the leg 22 and preferably extends for the full length thereof, as best illustrated in Figs. 2 and 3. The groove 28 is of a size and depth to receive the line 16 therein in such a manner that the same does not project beyond the surface of the face 24. Each of the legs 20 and 22 is preferably tapered longitudinally whereby the thickness of the L-shaped member is greatest at the junction between said legs, thereby affording requisite strength for the unit. Each of the legs may be provided with one or more longitudinally extending grooves in its outer surface to reduce

the cross-sectional area and the weight of the leg and provide strengthening ribs. For example, longitudinal grooves 32 may be formed in the leg 20 to define ribs 34 on opposite sides thereof, and the longitudinal groove 36 may be formed in at least a portion of the leg 20 to define the marginal reinforcing ribs 38.

In spaced relation to the juncture of the legs, the leg 20 is provided with a line-anchoring member 40. This line-anchoring member projects from the outer surface of the leg and preferably constitutes an integral substantially rectangular projecting block of metal whose opposite sides are grooved or undercut at 42 whereby said projecting member is formed in substantially T-shape. The grooves are preferably positioned with their lower surface portions substantially in the plane of the outer face of the leg 20.

At the outer or free end of the leg 20 is provided a pair of laterally projecting portions 44 whose inner surface lies in the same plane as the face 24 of the leg 20. The parts 44 form rigid wings at the free end of the leg which project substantially laterally therebeyond as illustrated, whereby the width of the member at the points 44 is substantially greater than the widest mortar joint commonly used by masons.

In the use of the device, one end of the line 16 is passed through the groove 28 of one of the members 18, being likewise passed through the slot 38 to pass around the end of the leg 20 at the juncture of the legs 20 and 22. The end of the line is then passed forwardly along the outer surface of the leg 20 and is wound around the member 40 seating in the groove 42 by which it is firmly clamped and retained when it is tightly looped by virtue of the frictional wedging or clamping action of the grooves upon the tightly drawn coils of the line which are seated therein. The line holder to which the line has been secured as aforesaid is then anchored at one end of the wall with the surface 26 of the leg 22 bearing flat against that end surface of the wall and the line is drawn taut and its opposite end is passed through the groove 24 and the slot 38 of a corresponding line holder positioned in horizontal alignment with the first named line holder, and the opposite end of the line is then drawn tight and anchored by coiling thereof around the member projection 49 and in the groove 42, as hereinabove described.

It will be apparent from the foregoing that the tension applied by the line acts in a plane substantially flush with the surface of the building wall and acts directly longitudinally upon the legs 20 of the opposite holders by virtue of the passage around the same through the groove 28 and the slot 38 of the construction, which is best seen in Fig. 2. Consequently, the tension of the lines serves to draw the opposite holders firmly against the opposite ends of the masonry structure with the surfaces 26 of the legs 22 thereof permitted to lie naturally in planes perpendicular to the line and flush with the end surfaces of the wall at which they are anchored. This positions the line in such a manner that it forms a guide close to the working surface and thereby avoids such spacing of the line as would occasion possibility of error as different mortar joints are viewed by the worker at progressively different angles as different courses of the work are laid up. At the same time it is not necessary to disturb the previous work in any way, as by driving nails in fresh mortar; also, it will be apparent

that, even though the line may be tensioned, it still has sufficient resilience to permit manipulation of the line holders to advance the same from step to step as the height of the wall increases.

While the width of the legs of the holder is slightly greater than the greatest width of a mortar line, it is desirable that that width be held to the lowest limits possible so that the size and the weight of the holder may be at a minimum to facilitate storage and handling of the unit. Also, there is some possibility that under certain circumstances it may be desirable to so position the holder that either the upper or the lower edge thereof is out of contact with a masonry element. For such purposes, the extensions 40 serve to stabilize the holders and insure firm positioning thereof. In other words, by virtue of the fact that the wings 44 project laterally from the leg 20, the user is assured that at the free end of the leg 20 a firm supporting face engagement with the masonry elements on opposite sides of the mortar joints will be obtained under all working conditions and regardless of the width of the mortar joint. The only condition in which one of the projections 44 might not have engagement with masonry elements on opposite sides of the mortar joints would be in a case where the member was so positioned with reference to the mortar joint that the top of one of the wings would project over the mortar joint. However, it will be apparent in such a condition, due to the proportion of the parts, at least a part of the leg 22 on opposite sides of the groove 38 would engage a masonry element and thus procure at the leg 22 instead of the wings 44 the desired stabilizing anchorage.

While the construction herein described and illustrated is preferred, it will be understood that changes may be made therein within the scope of the appended claim without departing from the spirit of the invention.

I claim:

A mason's line holder comprising an L-shaped member having rigid leg portions whose inner surfaces are flat throughout their full extent and positioned perpendicularly to each other, one leg having a central longitudinal groove in its inner surface extending the full length thereof and adapted to receive a line, the other leg having a longitudinal slot therein with which said groove communicates, a line anchoring member carried by said first leg and projecting from an intermediate portion of the outer face thereof, and rigid wings projecting laterally from the free end of said first leg at opposite sides thereof with their inner surfaces flush with the inner surface of said first leg.
